UNITED STATES PATENT OFFICE.

WALLACE SCOTT AND STEWART DUDLEY MARJORIBANKS, OF NEWCASTLE-UPON-TYNE, ENGLAND, ASSIGNEES TO SCOTTS HOUSEHOLD APPLIANCES LIMITED, OF NEWCASTLE-UPON-TYNE, ENGLAND, A COMPANY OF GREAT BRITAIN.

MEANS FOR EXCLUDING DRAFFS FROM UNDER DOORS.

Application filed April 20, 1927, Serial No. 185,153, and in Great Britain January 13, 1927.

This invention comprises a means for excluding drafts from under doors, and it consists of a horizontal member, the lower side of which is fitted with a felt or rubber or other suitable surface to form a pad, which engages the floor when the door is closed. The horizontal member is hinged to the lower part of the door by means of one or two horizontally arranged hinges which permit the horizontal member to be turned on a horizontal axis away from the door, so as to lift the engaging face off the floor as the door is opened. This hinging effect is secured by means of a double-hinged fitting applied to the door jamb at the hanging side and to the end of the horizontal member, the said double-hinged fitting comprising an angular central portion and two hinged plates, one for attachment to the door jamb and the other for attachment to the horizontal member, in such a way that the angular central plate may be connected to the door jamb and to the end of the horizontal member with the knuckles of the hinges being held approximately at similar angles to the floor, the apex of the axis of the hinges approximately intersecting the axis of the hinges which support the door, to which axis both knuckle joints converge and their axes intersect at the same point. The hinge plate which is attached to the door jamb at the hanging side, is attached in a plane parallel with the plane of the door surface, but the axis of the knuckle joint of the hinge plate which is attached to the horizontal member is contained in a plane oblique to the plane containing the surface of the door, such plane diverging outwards and in a downward direction.

In order that the invention may be clearly understood, reference is made to the accompanying drawings, in which

Figure 1 illustrates the draft excluder attached to the lower edge of the door;

Figure 2 is an enlarged view showing the two hinged plates, and the angular central plate all in the same plane.

Figures 3, 4, and 5 are respectively front elevation, sectional plan, and sectional end view, showing the horizontal member and the double hinged fitting in position when the door is closed, and

Figures 6 and 7 are respectively sectional plan and sectional elevation showing the

same parts in position when the door is open.

The horizontal member, which is marked A in the drawings, is shown constructed of wood. It is obvious, however, that such horizontal member could equally be made of any other substance.

B is a hinge near the outer end of the horizontal member for supporting the outer end of such horizontal member A, while permitting it to be turned on a longitudinal axis in order to lift the horizontal member away from the ground as the door is opened.

C is the angular central plate of the double-hinged fitting; D is the hinge plate for attachment to the door jamb; E is the hinge plate for attachment to the end of the horizontal member. These hinge plates D and E are hinged at the knuckle joints D' and E' to the angular central plate C.

As will be seen best at Figure 4, the axis of the knuckle joint E' inclines outwards in a downward direction. F is the surface attached to the horizontal member A, which, in the drawings, is illustrated as rubber piping surrounded with fabric which is attached at F' to the inner face of the horizontal member A. G is an additional hinge for connecting the horizontal member A to the door at an intermediate position. This hinge G permits the horizontal member A, after being fitted to the door by the hinge B and the double-hinged fitting, to be bent downwards in order to fill in any irregularity in the floor. When the door is opened, the opening angle is communicated to the horizontal member A by the movement of the door, and the double-hinged fitting divides this movement between the knuckle joint D' and the knuckle joint E'. If the hinge plates D and E were in the same plane, these axes would be on a dead centre and would result in the breakage of the double-hinged fitting owing to no lead being given for the double-hinged fitting to give angular movement in one direction or the other. It is to overcome this dead point that the axis of the hinge E' is inclined to the plane containing the surface of the door.

The effect of the opening of the door and the consequent angular movement imposed on the double-hinged fitting, is to turn the horizontal member outwards from the door, and thus lift the lower contact edge away

from the floor. The extreme limit of this movement is illustrated at Figure 7.

Although the double-hinged fitting has been illustrated with the hinges converging, each at an angle of 45° relatively to the floor, this angle can be varied within certain limits, providing the axes of the knuckle joints of the hinges maintain similar angles.

What we claim as our invention and desire to secure by Letters Patent is:—

1. In association with a draft excluder for doors in which a horizontal member is hinged to the lower portion of the door and is required to be automatically angularly turned on a horizontal axis when the door is opened, the combination of a double-hinged fitting, comprising a hinged plate for attachment to the door jamb, a hinged plate for attachment to the horizontal member, and an angle plate to which both hinges are jointed at equal angles, one of such hinge joints being inclined to the plane containing the face of the door, whereby angular adjustment is automatically given to the horizontal member by the opening of the door.

2. In association with a draft excluder for doors in which a horizontal member is hinged to the lower portion of the door and is required to be automatically turned on its hinges when the door is opened, the combination of a double-hinged fitting, comprising

ing a hinged plate for attachment to the door jamb, a hinged plate for attachment to the inner end of the horizontal member and an angle plate to which both hinges are jointed at right angles to each other, one of such hinge joints being inclined to the plane containing the face of the door, whereby angular adjustment is automatically given to the horizontal member by the opening of the door.

3. In association with a draft excluder for doors in which a horizontal member is hinged at its outer end to the lower portion of the door, and a hinge located about centrally between the horizontal member and the door, and is required to be automatically turned on its hinges when the door is opened, the combination of a double hinged fitting, comprising a hinged plate for attachment to the door jamb, a hinged plate for attachment to the inner end of the horizontal member, and an angle plate to which both hinges are jointed at right angles to each other, one of such hinge joints being inclined to the plane containing the face of the door, whereby angular adjustment is automatically given to the horizontal member by the opening of the door.

In witness whereof we have hereunto set our hands.

WALLACE SCOTT.
S. D. MARJORIBANKS.
